ELECTRIC VALVE STARTING SYSTEM

Max Hürlimann, Baden, Switzerland, assignor to
Aktiengesellschaft Brown Boveri & Cie, Baden,
Switzerland, a joint-stock company of Switzerland

Application July 3, 1936, Serial No. 88,719

6 Claims. (Cl. 175—363)

This invention relates in general to electric valve starting systems, and more particularly to a system for causing the continued operation of an ignition mechanism of the liquid jet type for a valve of the liquid cathode type and for causing such operation to cease upon establishment of a flow of exciting current through the valve. Electric valves of the liquid cathode type may advantageously be provided with a so-called igniting mechanism whereby a solenoid causes some of the cathode material to be projected momentarily as a jet against an ignition anode connected with a source of direct current, whereby an arc is struck between the ignition anode and the cathode upon breaking of the jet. It is, however, usually more convenient to avoid the use of such source of direct current and instead of such direct current, to supply alternating current or pulsating rectified current to the ignition anode. The moment of interruption of the jet may then occur when the voltage present between the ignition anode and the cathode is not sufficient to cause an arc to be established therebetween, or even when such voltage is of the wrong polarity. Under such circumstances it is necessary to continually impress current impulses on the solenoid to produce a series of jets between the cathode and the ignition anode, until a jet is broken while the voltage between the ignition anode and the cathode is of the proper magnitude and polarity, and to cause the operation of the solenoid to cease when a flow of excitation current is established through the valve. Such results are preferably obtained automatically by means of a relay having the coil thereof connected in parallel with the solenoid and of a second relay having the coil thereof connected in the excitation circuit of the valve. The proper operation of the system also requires that the output circuit of the valve be maintained open during operation of the starting system.

It is, therefore, one of the objects of the present invention to provide a starting system for an electric valve of the liquid cathode type, in which system jets of cathode material are continually produced between the cathode and an ignition anode.

Another object of the present invention is to provide a starting system of the liquid jet type for an electric valve having a liquid cathode, which ceases to function when a flow of excitation current is established through the valve.

Another object of the present invention is to provide a starting system for an electric valve of the liquid cathode type which may operate

only when the valve is disconnected from the output circuit thereof.

Objects and advantages other than those above described will be apparent from the following description when read in connection with the accompanying drawing, in which:

Fig. 1 diagrammatically illustrates an embodiment of the present invention in which the ignition anode of the valve receives a flow of alternating current;

Fig. 2 is a cross sectional view through the ignition mechanism of the valve illustrated in Fig. 1; and

Fig. 3 diagrammatically illustrates the modifications to be brought to the embodiment illustrated in Fig. 1 for supplying rectified current to the ignition anode of the valve.

Referring more particularly to the drawing by characters of reference, reference numeral 4 generally designates an electric valve having a casing 5 enclosing a liquid cathode 6 lying in a well 7 of the casing and a plurality of main anodes 8, but it will be understood that the present system is also applicable to the control of valves having a single main anode. Valve 4 may be utilized for any desired purpose but, in the present application, will be assumed to be employed as part of an alternating current rectifying system. Anodes 8 are accordingly connected with an alternating current supply circuit 9 through a transformer 11, the transformer being connected with one conductor of a direct current output circuit 12 having the second conductor thereof connected with cathode 6 through a circuit breaker 13. Valve 4 is provided with a plurality of excitation anodes 14, anodes 8 and 14 all extending through the casing 5 of the valve in insulated relation therewith. The valve is also provided with an ignition anode 16 adjacent the surface of cathode 6 and which may be insulated from the casing of the valve, but which may also be conductively connected therewith or may even constitute a part of the casing, which is generally insulated from the cathode.

The ignition mechanism of the valve is illustrated in detail in Fig. 2, and comprises a solenoid 17 arranged about an extension 18 of well 7. The extension is made of magnetic material and constitutes the fixed core of the solenoid. The solenoid is preferably supported by a cup shaped shield 19 bolted on extension 18 and cooperating with a washer 21 in closing the magnetic circuit of the solenoid. Extension 18 is hollowed to define a cylinder adapted to receive the movable armature 22 of the solenoid. The armature

is preferably so shaped as to engage the wall of the cylinder in substantially liquid tight relation therewith, and may be provided with a coating of non-magnetic material to prevent excessive magnetic attraction between the armature and the walls of the cylinder, which would result in excessive side thrust therebetween. Such coating may consist of a non-magnetic metal, of vitreous enamel, or any other suitable non-magnetic material. Armature 22 is urged upward under the action of a spring 23, such action being reinforced by the buoyancy of the armature resulting from the immersion thereof in the cathode material, which generally consists of mercury. The armature is drilled to form a nozzle directed toward ignition anode 16, and adapted to produce a jet of cathode material extending through cathode 6 and between the cathode and the ignition anode upon downward movement of the armature, from the rest position thereof shown, resulting from energization of solenoid 17. As a portion of the magnetic flux produced by the solenoid flows through the portion of the wall of the cylinder extending within the solenoid, such portion is preferably made as thin as is practically feasible.

The source of current for solenoid 17 and for anodes 14 and 16 may be any alternating current circuit such as circuit 9, the connection therebetween comprising a switch 24 and a transformer 26 having a primary winding 27 and having a secondary winding 28 provided with a plurality of terminals and with a midtap. Although transformer 26 is herein represented as a single-phase transformer, a polyphase transformer would be used if excitation anodes 14 were greater in number than two. The excitation anodes are connected with the terminals of winding 28 through current limiting resistors 29, and ignition anode 16 is connected with one of such terminals through a current limiting resistor 31 and through contacts 32 of a relay 33. Another relay 34 has the coil thereof connected in parallel with solenoid 17 and is provided with contacts 36 connecting the solenoid and the coil of relay 34 between two terminals of winding 28 through contacts 37 of relay 33. Relay 34 may be an inherently slow acting relay, or may be provided with suitable time delay means 35 operable to retard the closure of contacts 36. Relay 33 is provided with contacts 38 to complete a circuit for a signal device, such as a glow lamp 39, with secondary winding 28 upon operation of the relay. Cathode 6 is connected with the midtap of secondary winding 28 through a holding coil 41 for the latch 42 of circuit breaker 13, through the coil of relay 33, and through a reactor 43.

The operation of the system is initiated by closure of switch 24, whereby transformer 26 is energized from circuit 9. Current then flows from winding 28 through solenoid 17 and the coil of relay 34, through contacts 36 and through contacts 37 back to winding 28. Solenoid 17 accordingly attracts armature 22, thus causing a jet of cathode material to be produced between cathode 6 and ignition anode 16, relay 34 at the same time attracting the armature thereof to open contacts 36. Solenoid 17 and the coil of relay 34 are thus operatively disconnected from winding 28, and armature 22 and relay 34 return to the position shown. The relay is so designed that armature 22 returns to the rest position thereof before reclosure of contacts 36, such result being preferably obtained by the

provision of time delay means 35 on the relay. Upon the closure of contacts 36, solenoid 17 and the coil of relay 34 are reenergized and the above sequence of operation is repeated as long as contacts 37 remain closed. Solenoid 17 is thus caused to continually receive current impulses from winding 28, and the resulting reciprocating movement of armature 22 causes jets of cathode material to be continually projected and broken between cathode 6 and ignition anode 16. Each time such a jet is projected, current flows from winding 28 through resistor 31, ignition anode 16, cathode 6, coil 41, the coil of relay 33 and reactor 43 back to winding 28, such current being, however, insufficient in magnitude to cause operation of latch 42 or of relay 33. Such current is interrupted each time armature 22 reaches the fully attracted position thereof, the jet of cathode material produced by movement of the armature then being interrupted. A number of such successive interruptions may occur at instants at which ignition anode 16 is at a negative potential with respect to the potential of cathode 6, or is at a positive potential insufficient to cause an arc to be established between the ignition anode and the cathode.

After a few operations of solenoid 17, or sometimes even after the first operation thereof, the jet is broken when anode 16 is at a positive potential, with respect to the potential of cathode 6, such that an arc is drawn therebetween, such arc being characterized by the establishment of a so-called cathode spot at which cathode 6 emits electrons for the flow of current between any of the anodes of valve 4 and the cathode through the space confined within the valve. Upon establishment of such cathode spot, another arc is established between excitation anodes 14 and the cathode, and current flows from winding 28 through the resistors 29, excitation anodes 14, cathode 6, coil 41, the coil of relay 33 and reactor 43 back to winding 28. Such current is a rectified current, which is maintained continuous and substantially uniform by the action of reactor 43, although the voltage under which such current flows is a pulsating voltage decreasing to zero twice during each cycle of the voltage circuit 9. Such current is of sufficient magnitude as to cause relay 33 to operate in response thereto, to thereby operatively disconnect ignition anode 16 and solenoid 17 from winding 28, thus preventing any further operation of the ignition system. Relay 33 closes contacts 38, thus energizing lamp 39 which gives an indication that the starting operation of the valve is completed. Circuit breaker 13 may then be closed, and is maintained closed by latch 42, which is maintained in latching position by coil 41.

If the excitation current of valve 4 is interrupted for any reason, latch 42 is released by coil 41 and thus causes opening of circuit breaker 13. Relay 33 returns to the position shown, and the valve is started again in the manner above described provided that transformer 26 is energized. It is necessary to cause circuit breaker 13 to open before solenoid 17 begins to function, for the reason that if circuit breaker 13 remained closed and if an arc were struck between cathode 6 and ignition anode 16 while the ignition anode was at a negative potential with respect to the potential of the cathode, current could flow from transformer 11 through anodes 8, through ignition anode 16 then functioning as a cathode, through

resistor 31, contacts 32, winding 28, reactor 43, the coil of relay 33, coil 42 and line 12 back to transformer 11. The secondary voltage of transformer 11 being generally much higher than the voltage of winding 28, such current would be greater than the maximum current for which the ignition and excitation circuits are designed, and such circuits would be seriously damaged.

In the embodiment partially illustrated in Fig. 10 3 resistor 31 is connected with one terminal of winding 28 through contacts 32 of relay 33 and through one of a pair of rectifying devices 44, the resistor being also connected with the other terminal of winding 28 through additional contacts 15 46 of relay 33 and through the other device 44. In such manner, the flow of current between ignition anode 16 and cathode 6 during connection therebetween through a jet is unidirectional, and an arc may be established at the cathode during 20 either half cycle of the voltage of supply circuit 9. However, it is again necessary to provide for repeated operation of solenoid 11, as a jet established between cathode 6 and ignition anode 16 may be broken while the ignition anode is at 25 substantially cathode potential, so that an arc would not be established between the ignition anode and the cathode until after another operation of the solenoid. Once such arc is established, the flow of current through ignition anode 30 16 is maintained continuous and substantially uniform by the action of reactor 43, so that the cathode spot of cathode 6 is maintained even if the flow of current through excitation anodes 14 establishes itself several cycles after the establishment of the arc between the ignition anode 35 and the cathode.

Although but two embodiments of the present invention have been illustrated and described, it will be apparent to those skilled in the art that 40 various modifications and changes may be made therein without departing from the spirit of the invention or from the scope of the appended claims.

It is claimed and desired to secure by Letters 45 Patent:

1. In combination, an electric valve comprising a casing enclosing a liquid cathode and an ignition anode, a solenoid having an armature adapted upon attraction thereof by said solenoid from a rest position to cause a jet of cathode material to be projected from said cathode to said ignition anode, a source of current connected with said solenoid, and a relay having a coil connected in parallel with said solenoid and having contacts 50 controlling therethrough the supply of current from said source to said solenoid and said relay coil whereby the supply of said current to said solenoid and relay coil is simultaneously interrupted and the said solenoid is caused to continually receive current impulses from said source.

2. In combination, an electric valve comprising a casing enclosing a liquid cathode and an ignition anode, a solenoid having an armature adapted upon attraction thereof by said solenoid from a rest position to cause a jet of cathode material to be projected from said cathode to said ignition anode, a source of current connected with said solenoid, a relay having a coil connected in parallel with said solenoid and having contacts 55 opening upon operation of said relay to operatively disconnect said source from said solenoid and from said relay coil, and means for delaying reclosure of said relay contacts until after return of said solenoid armature to the rest position.

3. In combination, an electric valve comprising a casing enclosing a liquid cathode and an ignition anode, a solenoid having an armature adapted upon repeated attraction thereof by said solenoid from a rest position to cause a succession of jets of cathode material to be projected from said cathode to said ignition anode, a source of current connected with said solenoid, a relay having a coil connected in parallel with said solenoid and having contacts controlling therethrough the supply of current from said source to said solenoid and said relay coil whereby the supply of said current to said solenoid and relay coil is simultaneously interrupted and the said solenoid is caused to continually receive current impulses from said source, and means for connecting said source with said ignition anode and said cathode to cause an arc to be established therebetween upon interruption of one of said jets of cathode material. 20

4. In combination, an electric valve comprising a casing enclosing a liquid cathode, an ignition anode and a plurality of excitation anodes, a solenoid arranged outside of said casing and having an armature immersed in said cathode 25 and adapted to produce a jet of cathode material between said cathode and said ignition anode upon energization of said solenoid, an alternating current supply circuit, a transformer having a primary winding connected with said supply circuit and having a secondary winding provided with terminals and with a midtap, means for connecting said excitation anodes with said transformer terminals, means for connecting said ignition anode with one of said transformer terminals, a relay having a coil connected in parallel with said solenoid and having contacts connecting said solenoid and said relay coil between two of said transformer terminals whereby said solenoid is caused to continually receive current impulses from said transformer, and a second relay 30 having a coil connecting said cathode with said transformer midtap and operable in response to the flow of excitation current therebetween to disconnect said ignition anode and said solenoid 35 from said transformer. 40

5. In combination, an electric valve comprising a casing enclosing a liquid cathode, a plurality of main anodes and of excitation anodes, and an ignition anode, a solenoid having an 50 armature immersed in said cathode and adapted to produce a jet of cathode material between said cathode and said ignition anode upon energization of said solenoid, an alternating current supply circuit, a direct current load circuit connected with said supply circuit, a circuit breaker connecting said load circuit with said cathode, a transformer having a primary winding connected with said supply circuit and having a secondary winding provided with terminals and with a midtap, means for connecting said excitation anodes with said transformer terminals, means for connecting said ignition anode with one of said transformer terminals; a relay having a coil connected in parallel with said solenoid 55 and having contacts connecting said solenoid and said relay coil between two of said transformer terminals, whereby said solenoid is caused to continually receive current impulses from said transformer, a second relay having a coil connecting said cathode with said transformer midtap and operable in response to the flow of excitation current therebetween to disconnect said ignition anode and said solenoid from said transformer, and means for causing opening of said 60 transformer, and means for causing opening of said 70 transformer, and means for causing opening of said 75

- circuit breaker upon interruption of said excitation current.
6. In combination, an electric valve comprising a casing enclosing a liquid cathode, an ignition anode and a plurality of excitation anodes, a solenoid arranged outside of said casing having an armature immersed in said cathode and adapted to produce a jet of cathode material between said cathode and said ignition anode upon energization of said solenoid, an alternating current supply circuit, a transformer having a primary winding connected with said supply circuit and having a secondary winding provided with terminals and with a midtap, means for connecting said excitation anodes with said trans-

former terminals, rectifying means connecting said transformer terminals with said ignition anode to supply unidirectional current thereto, a relay having a coil connected in parallel with said solenoid and having contacts connecting said solenoid and said coil between two of said transformer terminals whereby said solenoid is caused to continually receive current impulses from said transformer, and a second relay having a coil connecting said cathode with said transformer midtap and operable in response to the flow of excitation current therebetween to disconnect said ignition anode and said solenoid from said transformer.

MAX HÜRLIMANN. 15
